To all whom it may concern:

Be it known that I, Robert Edwin Dietz,
of the City, County, and State of New York, have invented or produced
a new design or figure to be cast in brass or other metal, which when
finished are intended to ornament Girandoles or candelabra; And I
do hereby declare that the following is a full and exact description of

the same. Fig 1. represents the figure of a man, the right arm elevated even with the head, the left arm holding a crop. Figs 2.-Fig 3. 3. a mantle over the right arm and left shoulder and resting on the ground. Figs 4. 4. a stump & tree. Fig 5. a girdle. - Fig 6. vestine of hair. Fig 7 a shell to drink from. Figs 8, 8. foliage and flowers. Fig 9 rocks.

What I claim as my production and desire to secure by Letters Patent is. The arrangement and combination of the foliage, drapery, human figure, and flowers, as set forth in the accompanying drawings forming an ornamental design for a girandole.
